[57] CLAIM

The ornamental design for an electric bicycle with pedal torque enable unit, as shown and described.

DESCRIPTION

FIG. 1 is a front elevation view of an electric bicycle with pedal torque enable unit showing my new design;
FIG. 2 is a rear elevation view thereof;
FIG. 3 is a left side elevation view thereof;
FIG. 4 is a right side elevation view thereof;
FIG. 5 is a top plan view thereof; and,
FIG. 6 is a bottom plan view thereof.

The broken lines disclosure illustrated in the drawings are for illustration purposes only and form no part of the claimed design.
